UNITED STATES PATENT OFFICE.

EUGÈNE CHASSAING, OF PARIS, FRANCE, ASSIGNOR TO MARCEL DUFOUR, EMILE JACQUELIN, AND RENÉ ACHILLE HENRY, ALL OF PARIS, FRANCE.

STRETCHER.

1,246,544.

Specification of Letters Patent.

Patented Nov. 13, 1917.

Application filed February 3, 1916. Serial No. 75,951.

To all whom it may concern:

Be it known that I, EUGÈNE CHASSAING, of 4 Boulevard Saint-Marcel, Paris, Republic of France, doctor of medicine, have 5 invented Improvements in Stretchers, of which the following is a full, clear, and exact description.

At the present time, all questions relating to the amelioration of the lot of the sick or 10 wounded are of the first importance. In particular, the transport of the wounded and the sick, without aggravation of their condition, has been at all times one of the primary considerations of physicians and 15 surgeons.

Stretchers now in existence for transporting the sick or wounded do not give satisfaction to medical practitioners and in particular supply their two principal desiderata, which are:

I. Transport of the sick or wounded person without liability of his being infected during the transport by spots or stains left 25 by the wounded or sick person who has preceded him on the stretcher, and without himself being liable to infect the wounded or sick person who will be transported after him.

II. Bringing of the patient on to or out 30 from the stretcher with the minimum of shock and movement, in order to avoid aggravation of his condition, in particular hemorrhage, etc.

In order to solve this double problem, it is 35 only necessary to have in the first case a stretcher which can be easily sterilized between two transports of wounded or sick persons, and in the second place, that the wounded or sick person can be placed 40 without any shock on the stretcher, and from the stretcher on to his bed or on to the operating table.

A large number of inventors have endeavored to find a practical solution; all in 45 agreement with the practitioners have unanimously recognized that a stretcher with its canvas or fabric part removable and interchangeable would completely satisfy this double desideratum.

Unfortunately, up to the present, none of 50 the patterns of stretcher with removable canvas or fabric has been found to be practical; all the inventors have been baffled by a difficulty which they have not been able to 55 overcome in a simple and practical manner.

This difficulty, which has not been surmounted, is the method of attachment of the canvas or fabric to the rigid frame.

The improvement which forms the object of this invention, consists in mounting the 60 canvas or other fabric, hereinafter referred to as canvas, on the stretcher by means of a flexible beading arranged on the two sides of this canvas which is slid into two grooves of equivalent form formed on the longitudinal members or poles of the said 65 stretcher. The beading at the sides of the canvas fulfil the part of slides, while the grooves in the longitudinal members fulfil the part of guide ways, as in a drawer.

This method of mounting the canvas is a simple and economical solution of the problem and it has the advantage of being applicable to all existing types of stretcher.

This invention will be hereinafter described by way of example with reference to the accompanying drawing, in which:

Figure 1 shows in transverse section a first form of construction of the improved stretcher forming the object of this invention.

Fig. 2 shows in transverse section a second form of construction of the improved stretcher herein referred to.

Fig. 3 shows in transverse section a third form of construction of my improved stretcher.

Fig. 4 is a plan view of the improved stretcher shown in Fig. 2.

In the improved stretcher forming the object of this invention, see Fig. 1, the two longer sides of the canvas *a* are provided with a flexible beading *e* formed by a cord, a leather band, a spiral spring, etc., inserted in a hem *f* forming a slide. On the other hand, 90 over the whole length of each of the longitudinal members *b* of the stretcher where the canvas is generally fixed, a groove *g* is formed, serving to receive the beading *e* which plays the part of a slide, while the 95 groove plays the part of a guide-way. This groove has toward the exterior a very narrow lateral opening *g'* through which passes the canvas *a*.

The lateral opening *g'* of the said groove 105 *g* is enlarged at its two ends in such a manner as to allow the flexible beading *e* and the hem of the canvas to pass freely.

In order to place the canvas on the stretcher, it is only necessary to introduce 110

the two flexible beadings *e* simultaneously into the grooves *g*, then this canvas is fixed at its two ends in any suitable manner but in any case so that the canvas is removable.

- 5 It is easy to see, by examining Fig. 1, that the flexible beading *e* cannot pass through the aperture *g'* of the groove and that, in order to withdraw the canvas, it is necessary to slide the beadings like a drawer 10 in the grooves toward one or the other end of the stretcher. The placing in position and removal of the canvas only require a few moments.

This improvement, as will be seen, satisfies 15 the first desideratum, viz., a removable and interchangeable canvas. It also satisfies the second desideratum above mentioned, viz., to leave the sick or wounded person on the canvas of the stretcher in order to place him 20 in his bed or on the operating table without any shock. It is only necessary, in fact, to take each of the four corners of the canvas *a*, the wounded or sick person being above, and to pull in the direction of the arrow, 25 see Fig. 3, the two longitudinal members *b* at the sides of the canvas, which thus forms a kind of hammock in which the wounded person lies and can be placed where desired, this can be done without any shock.

30 The wounded person with his stretcher can also be placed in his bed or on the operating table; the two longitudinal members are then withdrawn, after having folded one of the transverse members or distance pieces 35 *h*, by sliding them in such a manner that the canvas only remains in place with the sick or wounded person thereon.

In the example of construction shown in Fig. 2, the groove *g* is formed of two tube- 40 segments *g²* of metal fixed on the outer edge of the longitudinal members *b* by means of nails or screws *i*.

These tube-segments reinforce the longitudinal members or poles *b* to which they are applied.

45 In the example of construction shown in Fig. 3, the groove *g* is formed by two tube-segments *g²* formed integrally with a plate *g³* fixed to the outer side of the longitudinal members *b* by means of nails or screws *i*.

50 Claims.

1. A stretcher comprising two longitudinal members having longitudinal recesses, and a canvas provided with a flexible beading in each of its longitudinal edges, said 55 beadings engaging the recesses of said members.

2. A stretcher comprising two longitudinal members or poles, a canvas provided with hemps on its longitudinal edges, a flexible beading in each of these hemps, a longitudinal recess formed in each of the longitudinal members and adapted to receive the flexible beading in the hem of the canvas.

60 3. A stretcher comprising two longitudinal members or poles, a canvas provided with hemps on its longitudinal edges, a flexible beading in each of the hemps, a longitudinal recess formed in each of the longitudinal members and consisting of a groove 70 having a circular section, the diameter of which is slightly greater than that of the flexible beading, and a slot of reduced width opening on to the outside face of the longitudinal member.

75 The foregoing specification of my improvements in ambulance stretchers and wheeled ambulances serving for the transport of wounded or sick persons, signed by me this eleventh day of January, 1916.

EUGÈNE CHASSAING.
